UNITED STATES PATENT OFFICE.

HARRY M. HATFIELD, OF CHICAGO, ILLINOIS.

GAME.

1,161,770.

Specification of Letters Patent. Patented Nov. 23, 1915.

Application filed February 19, 1914. Serial No. 819,709.

To all whom it may concern:

Be it known that I, HARRY M. HATFIELD, a citizen of the United States, residing at Chicago, in the county of Cook and State of Illinois, have invented certain new and useful Improvements in Games, of which the following is a description.

My invention belongs to that general class of devices known as games, and relates particularly to the well known game of baseball.

More particularly it relates to an in-door or parlor baseball card game. With modifications, however, the game is adapted for playing games other than baseball.

The invention has among its objects the production of an indoor or parlor game of the kind described that is attractive, entertaining, simple, and which, in so far as possible, will resemble the actual game of baseball, with all the thrills, uncertainties, and unexpected happenings to be had in the ball park, thereby compelling interest and excitement on the part of the players.

It also has among its objects the production of a game which may be played with scores similar, or as much like the regular game of baseball as possible, as compared with the average baseball as played by major leagues' baseball teams, and contains all the various plays possible on various situations, preferably arranged so that the percentages of play and scores in the game correspond to a large extent with the actual game.

To this end my invention consists in the novel construction, arrangement, and combination of parts herein shown and described, and more particularly pointed out in the claims.

In the drawings, wherein like reference characters indicate like or corresponding parts, Figure 1 is a plan view of a game board suitable for use in the game herein described; Figs. 2, 3, 4, 5, 6, 7, 8, 9 and 10 are plan views of several cards employed in the game; Figs. 11 and 12 are similar views of modified forms of cards; Fig. 13 is a plan view of a portion of a board provided with a chart adapted to be used with the cards shown in Figs. 11 and 12; Figs. 14 and 15 are plan views of other modified forms of cards; Fig. 16 is a plan view of another form of board and chart, and Figs. 17 and 18 are perspective views of suitable markers.

Referring to the drawings, in which sev-

eral forms of my game are shown, it may be mentioned that the preferred form of games is illustrated in Figs. 1 to 10 inclusive. It may be first said, in order that the detail description may be clear, that the complete game consists of a deck of cards, and a board and markers, which board and markers are preferably employed for convenience in playing the game. As is well known to those who are familiar with the American national game of baseball, there are eight possible different situations in each half inning of the game, to-wit, batter up with no men on bases; batter up with a man on first base; batter up with men on first and second bases; batter up with men on second alone; batter up with men on first and third bases; batter up with a man only on third; batter up with men on second and third bases, and the batter up with all the bases full. In my game I preferably provide a plurality of cards, each suitably indicating one or more of these possible situations, and the play suitable for the actual situation indicated. While each single card may indicate but one situation and the play suitable therefor, I preferably combine the eight situations on each card, and indicate thereon, in conjunction with the situation, a play suitable for each condition or situation. By so doing the number of cards is very materially reduced, and the playing of the game is greatly facilitated. The board and markers herein described are merely for the convenience of the players in keeping track of the condition of the game, so that the particular situation at the time of playing each card may be readily determined.

With the preceding brief description of the game, reference may be had to the accompanying drawings.

Referring first to Fig. 2, a card is shown illustrating one of the complete packs of cards, it being understood that the particular plays indicated on the cards may be varied as desired. The card shown is arranged to cover the situations previously mentioned and indicated thereon at 2, 3, 4, 5, 6, 7, 8 and 9 respectively. At 10, 11, 12, 13, 14, 15, 16 and 17 respectively, are indicated plays suitable for each of the situations referred to. If desired, the several situations may be divided by lines 18 and 19, for convenience in finding the particular situation on the card. Additional cards

20, 21, 22, 23, 24, 25, 26 and 27 are shown in Figs. 3 to 10 inclusive, as illustrative of various other cards, it being understood that there may be any number of cards in the deck, or that any desired number of cards in the deck may be used. As a matter of fact, in the preferred form of the game, sixty cards may be provided. Some of these cards may, of course, be duplicates, if so desired, or the different combinations or plays on the cards may be varied. In playing the game, the cards are shuffled before each half inning, and they are then placed face downward on the table, the player taking the topmost card from the deck. After recording his play, as directed, he places the card face on the table, apart from the pack. The person who is playing, or that is, who is supposed to be at bat, plays until the completion of three outs, as in the out-door game, after which the next player takes his turn at drawing the cards and recording his plays, as directed, until he has three outs.

25 In Fig. 1 is shown a board 28 arranged in a particularly convenient manner for recording or indicating the different situations, as well as the standing of the player during his inning. Referring to this figure, 29 indicates a suitable diamond having the home plate and first, second and third bases suitably designated. There may also be provided on the board suitable space 30 for designating the number of outs, suitably designated spaces 31 for indicating the strikes, suitable spaces 32 for indicating the number of balls, and likewise, a space, if so desired, for indicating the number of runs. The standing of the player is recorded or indicated, preferably by using suitable markers 48, 49, or their equivalents for the purpose, which may be moved about the board and placed upon the different designated spaces to indicate the player's standing. If desired, the markers may be of different colors, as for example, one player might have red markers and the other blue.

It is believed that the playing of the game will be obvious from the preceding. However, it may not be amiss to give a brief description of playing the game, which will tend to make clearer the modified forms hereafter described. If there is not a man on any base, the person playing, in turning over his card, refers to the batter-up space, as, for instance, referring to card 1, and for this situation the batter would be out, and another card is drawn, if not the third out. If, however, for instance card 20, had been drawn, the batter would take his base on balls. The same would be true if card 24. If, however, card 25 was drawn, it would count for a three-base hit. The player would place a marker

on the board corresponding with the indicated play. He would then draw the next card, for example, assume that it were card 26, and card 25 had been the one previously drawn, and the situation in this case is, a man on third base only. Referring to card 26, for this situation we find that the batter is out, but the man on third makes one run. In case there is a repetition of ball or strike, and the marker is moved to the space designated, ball two, strike two, or three, etc., depending upon the standing of the player. The usual baseball rules apply, and four balls constitute a base, three strikes an out, three outs a half inning, etc.

Figs. 11, 12 and 13 illustrate another form of the game, in which 33 and 36 are two cards only of the set. As shown, the card 33 is provided with a designated situation 34, the play being indicated by a suitable character, as for example, numeral 120. A chart is provided carrying the identifying play characters, so that reference may be had to the chart, so as to translate the character. In Fig. 13 I have illustrated the board 37 having a chart arranged thereon, only a portion of the same being shown. Referring to this figure, 38 indicates the identifying characters, in this case numerals, and 39 the translation, so that by referring to the board the particular play may be determined.

Figs. 14 and 15 show the situations bearing numerals, the particular play being written out in full. Only two cards 40 and 41 are shown. Referring to Fig. 14, card 40 is provided with the situation characters 42, and the play, information or directions 43, 44, etc., in this case the board 45 provided with a diamond 46, and any suitable means for recording the standing of the game, if so desired. I have shown characters 47 on the board, translating different situations on the cards. It is needless to say that these forms of cards and boards shown in Figs. 11 to 16 are merely for illustration of a portion of the modified form of the game. Any other identifying characters for designating the situations or plays may be employed, as previously set forth, if so desired, and the cards may be arranged with only one situation and its appropriate play on a card. In this case, however, it might be necessary to play several cards before a card having the proper situation upon it would be reached, and the numbers of cards would be multiplied by the number of stations. It is, of course, obvious that the situations may be placed upon the card in the same manner as the placing of characters on the ordinary playing card, so that the same may reach from either end, obviating the turning around of the card, as might be the case if the cards were made to reach from only

one end. This may be done by duplicating the situations of the plays of the card, *i. e.*, dividing it into sixteen spaces in the case shown, or by putting the reversal of the 5 same in some sections. This is merely mentioned, and it is not considered necessary to illustrate the same. In Figs. 17 and 18 I have shown two of the markers 48 and 49, and as was previously stated, one may 10 be of one color and the other of another color, so as to distinguish the two sides. Two, four, or any number of persons may play the game, or one person may play it as solitaire, making the plays for both teams. 15 Leagues may be organized and the game played after the manner of progressive euchre, cinch, or the like.

I have not endeavored in the drawings to illustrate the game as applied to other subjects than baseball, but from the preceding description and the illustrations of the same, as applied to baseball, its application to foot ball, tennis, golf, and other sports, or games, will be obvious.

25 Having thus described my invention, it is obvious that various modifications may be made in the same without departing from the spirit of my invention; hence I do not wish to be understood as limiting myself to 30 the exact form, construction, arrangement or combination of parts herein shown and described, or uses mentioned.

What I claim as new and desire to secure by Letters Patent is:

35 1. In a game of the kind described, a plurality of playing cards each provided with means for indicating a possible situation in the game, and with means for indicating a complete play or move suitable for 40 that situation.

2. In a game, a plurality of playing cards, each provided with identifying characters for indicating a plurality of different possible situations that might arise in the game, 45 and with means for indicating a complete play and result suitable for each situation.

3. In a baseball game, a playing card arranged to indicate eight possible situations at the time of the playing of the card, and 50 provided with means for indicating a proper play for each situation.

4. In a baseball game of the kind described, the combination of a plurality of playing cards, each arranged to indicate a 55 plurality of possible situations or standing of the team at bat in an inning, and with means for indicating a play or move proper for each indicated situation.

5. In a baseball game, a plurality of cards, 60 each card provided with suitable identifying characters thereon for representing eight different situations possible in every game

of baseball, in any half inning, each indicated situation provided with means for indicating a play suitable to each indicated 65 situation, whereby the player is directed to make a certain move, depending upon the particular situation at the time of the play.

6. In a baseball game of the kind described, and in combination, a game board 0 having properly designated spaces thereon, indicating home, first, second and third bases, a plurality of markers for indicating the players, a plurality of cards, each having properly designated spaces thereon, indicating 75 possible situations in a baseball game, to-wit, batter-up, man on first, man on first and second, man on second, man on first and third, man on third, man on second and third, and bases full, and provided with 80 means for indicating a proper play suitable for the situation as indicated by the places of the markers on the board.

7. In a baseball game, the combination 85 of a suitable board provided with the representation of a baseball diamond thereon, a plurality of markers for representing players, and indicating the condition of the bases at all times, and a plurality of playing cards, each provided with means for indicating the various possible arrangements 90 of the markers on the board, and with means for designating a possible play by the batter suitable to the arrangement of the markers on the board, and indicating the effect of 95 the play on any other player on the bases, and their further condition as a result of the play.

8. In a baseball game of the kind described, the combination of a plurality of 100 dissimpar playing cards, each card having spaces properly designated to indicate a plurality of situations suitable for the teams at bat, and identifying characters to indicate a particular play for each situation, 105 whereby a play to be made is completely determined by the situation met with at the time the play is made.

9. In a baseball game, a plurality of substantially dissimilar cards, each bearing 110 suitable inscriptions thereon for designating a play by the batter, common in a baseball game, and the effect of the play on the batter as well as the effect on any preceding batter or batters on the bases who have not 115 scored.

In testimony whereof, I have hereunto signed my name in the presence of two subscribing witnesses.

HARRY M. HATFIELD.

Witnesses:

ROY W. HILL,
CHARLES I. COBB.

It is hereby certified that in Letters Patent No. 1,161,770, granted November 23, 1915, upon the application of Harry M. Hatfield, of Chicago, Illinois, for an improvement in "Games," an error appears in the printed specification requiring correction as follows: Page 3, line 101, claim 8, for the word "dissimpar" read *dissimilar*; and that the said Letters Patent should be read with this correction therein that the same may conform to the record of the case in the Patent Office.

Signed and sealed this 11th day of January, A. D., 1916.

[SEAL.]

J. T. NEWTON,

Acting Commissioner of Patents.
